UNITED STATES PATENT OFFICE.

ANDREW F. MCGRATH, OF NEW YORK, N. Y.

TENT.

SPECIFICATION forming part of Letters Patent No. 748,974, dated January 5, 1904.

Application filed May 20, 1903. Serial No. 157,962. (No model.)

To all whom it may concern:

Be it known that I, ANDREW F. MCGRATH, a citizen of the United States, residing at New York, in the county of New York and State of New York, have invented certain new and useful Improvements in Tents, of which the following is a specification, such as will enable those skilled in the art to which it appertains to make and use the same.

The object of this invention is to provide an improved tent which is simple in construction and operation and which may be used by camping parties, military authorities, and others; and with this and other objects in view the invention consists in a tent constructed as hereinafter described and claimed.

The invention is fully disclosed in the following specification, of which the accompanying drawings form a part, in which the separate parts of my improvement are designated by suitable reference characters in each of the views, and in which—

Figure 1 is an end view of a tent made according to my invention; Fig. 2, a side view thereof; Fig. 3, a plan view thereof; Fig. 4, a plan view extended of one of the parts from which my improved tent is made; Fig. 5, a similar view of another of said parts; Fig. 6, a section on the line 6-6 of Fig. 3, and Fig. 7 a longitudinal section of a detail of the invention.

In the practice of my invention I provide two upright supports *a*, which in the form of construction shown consist of ordinary posts, having brace or stay cords *a*², secured to the posts, pegs, or similar devices *a*³, and in this case the posts *a* are set into the ground; but trees or other supports may be employed in place of the posts *a*.

Stretched between the posts *a* and connected therewith by rings or hooks *a*⁴ is a cord or cable *b*, and the connection between the cord or cable *b* and rings or hooks *a*⁴ is made by means of spring devices *c*, consisting, as shown in Fig. 7, of casings *c*², each end of which is provided with a hook *c*³, the shanks of which pass into the casing *c*² and are provided each with a head *c*⁴, and between the heads *c*⁴ of the shanks of the hooks *c*³ and the ends of the casing *c*² are placed springs *c*⁵.

The body portion of the tent, which is des-

ignated as a whole by the reference character *d*, is composed of transversely-arranged strips *d*², of canvas or other suitable material, which are passed over the cable or cord *b* and are provided at a predetermined distance from the edge thereof with longitudinal strips *d*³, which are secured thereto, and the body portion *d*⁴ of the strips *d*² form the top portion of the tent, while the side portions *d*⁵ thereof form the side walls of the tent, as clearly indicated in Fig. 6, while the strips *d*³ form eaves, and to these strips are secured stay-cords or similar devices *e*, which are connected with posts or pegs *f* in the usual manner. Each of the transverse strips *d*² is also provided, preferably, with an opening *g*, closed by a flap *g*², and said transverse strips are provided at their adjacent edges with a fly *h*, and said transverse strips *d*² are also connected by lacing, as shown at *i*, and in making this connection the flies *h* are gathered within the lacing, and this makes a secure connection.

The end transverse strips *d*² of the body portion of the tent are provided with triangular flaps or flies *j*, which form the ends of the tent, and which are connected by lacing *j*², and this connection may be made as closely as desired, as may also the separate tent section or strip.

It will thus be seen that my improved tent is composed of separate transverse sections or strips of flexible material supported by a cord or cable connected with suitable end supports, and when made in this way the tent may be taken down and packed in a very small space or receptacle whenever desired, and may be easily and conveniently set up whenever necessary, and by reason of these facts my improved tent is particularly adapted for use by traveling or camping parties and also by soldiers.

Having fully described my invention, what I claim as new, and desire to secure by Letters Patent, is—

A tent composed of separate sections of flexible material passed over a supporting cable which is longer than the tent and provided at each end with helical spring attaching devices, the separate sections being also provided with supplemental transverse strips which form side eaves, the end sections be-

ing also provided with flies which form the ends of the tent, stays connected with said eaves and end supports with which the helical spring attaching devices are connected 5 and the distance between which is greater than the length of the tent, substantially as shown and described.

In testimony that I claim the foregoing as

my invention I have signed my name, in presence of the subscribing witnesses, this 18th day of May, 1903.

ANDREW F. MCGRATH.
